UNITED STATES PATENT OFFICE.

GLENN H. CURTISS, OF BUFFALO, NEW YORK, ASSIGNOR TO CURTISS AEROPLANE AND MOTOR CORPORATION, A CORPORATION OF NEW YORK.

HYDROAIRCRAFT.

1,296,630.

Specification of Letters Patent. Patented Mar. 11, 1919.

Application filed February 28, 1917. Serial No. 151,504.

To all whom it may concern:

Be it known that I, GLENN H. CURTISS, a citizen of the United States, residing at Buffalo, in the county of Erie and State of New York, have invented certain new and useful Improvements in Hydroaircraft, of which the following is a specification.

My invention relates to aircraft and has reference more particularly to hydroaero-10 planes and flying boats in which the pontoon of the former and the hull of the latter are equipped with elongated longitudinally non-salient bottoms imparting such stability to the craft that it can not oscillate about a 15 transverse axis while traveling at speed on the surface of the water and preparatory to aerial flight.

Most, if not all successful hydro-aero-ma-20 chines have heretofore been characterized by one or more flotation bodies having a lower surface of longitudinal saliency ex-25 tended rearwardly considerably beyond the transverse vertical plane of the center of gravity or with a surface so constructed that 30 its rearward terminus acts as a transverse edge about which the craft may be rocked. In this way, after gaining speed and while hydroplaning, the angle of incidence of the supporting surfaces may be suddenly in-35 creased by depressing the tail end of the craft, and the necessary lift obtained to pull the machine from the surface of the water while skimming thereover. Fore and aft oscillation about a transverse edge or step 40 in the vicinity of the transverse vertical plane of the center of gravity has been relied on to secure the necessary vertical lift in taking to the air from the surface of the water.

By the present invention it is proposed 45 to deviate or depart from the standard practice and instead provide a machine in which the bottom surface is non-salient and the aeroplane wings or supporting surfaces 50 fixed permanently in such relation to the flotation body as to make an angle with the keel line equal to the calculated angle of incidence, *i. e.*, the angle giving the maximum lift-drift ratio or a ratio sufficient 55 to pull the craft from the surface of the water without rocking the body fore and aft.

The invention is further characterized by 60 shaping the body of a symmetrical streamline form about an axis making with the

chord line of the wings an angle equal to 55 the flying angle of incidence for maximum speed or at least for a lift-drift ratio con-60 siderably less than maximum. Furthermore, it is proposed that the effective line of thrust be arranged parallel to the longitudi-65 nal axis of the flotation body or at least at an angle thereto, forwardly and downwardly inclined, and not greater than the angle which said body makes with the keel line. 65

Of the drawings, wherein like characters of reference designate like or corresponding parts:

Figure 1 is a side elevation of a hydro-70 aeroplane characterized as herein pointed out;

Fig. 2 is a similar view illustrating the machine positioned for maximum climbing efficiency;

Fig. 3 is a view similar to Fig. 1 illustrat-75 ing a flying boat, and

Fig. 4 illustrates the flying boat in a manner similar to the illustration of Fig. 2.

In the embodiment of the invention selected for illustration, 10 designates the 80 fuselage, 11 the pontoon or flotation body, 12 the supporting surfaces, 13 the empennage, and 14 the propelling power plant of a hydroaeroplane capable of gaining aerial flight from the surface of the water without 85 tail depression. The bottom of the pontoon 11 is longitudinally non-salient and of hydroplaning form although transversely stepped as indicated at 15 at a point considerably in advance of the transverse vertical plane of the center of gravity C. G. 90 Fore and aft oscillation of the craft with the step 15 as an axis is prevented. In other words, the machine may be described as stable fore and aft by reason of its elongated non-salient bottom. 95

In view of the bottom formation of the pontoon 11 it is proposed that the aeroplane wings or supporting surfaces 12 shall be 100 fixed permanently in such relation thereto as to make an angle with the keel line designated 20 equal to the maximum flying angle of incidence, *i. e.*, the angle giving the maximum lift-drift ratio or at least a lift-drift ratio sufficient to pull the boat from the surface of the water while skimming thereover. 105

The pontoon 11 is symmetrically streamlined about an axis 21 making with the

chord line 22 of the supporting surfaces an angle equal to the flying angle of incidence for maximum speed or at least for a lift-drift ratio considerably less than maximum. 5 The keel line 20 thus makes with the axis 21 an angle greater than the angle of incidence for maximum speed.

The line of thrust of the craft is arranged parallel to said axis 21 or at least 10 some angle thereto, forwardly and downwardly inclined and not greater than the angle which said axis makes with the line 20 indicating the keel line of the pontoon. In other words, the interior angle formed by 15 the line of thrust, designated 23 and the line 21, is never to be greater than the interior angle formed by said line 21 and the keel line 20.

For an understanding of the principles 20 here involved, I have assumed that the angle of incidence for maximum speed is two (2°) degrees and that the angle of incidence for maximum climb is eight and a half ($8\frac{1}{2}^\circ$) degrees (both of these angles may be varied). Six and a half ($6\frac{1}{2}^\circ$) degrees or the 25 difference between the angle of incidence for maximum speed and the angle of incidence for maximum lift I have calculated as best for the angle formed by the lines 21 and 20 30 indicating respectively the axis of the pontoon 11 and the keel line thereof. When at rest upon the surface of the water and unsupported by air reaction on the surfaces 12, the lower half of the pontoon is completely 35 submerged. After starting, and as the machine speeds up, the hydroplaning bottom of the pontoon 12 causes the machine to gradually shift from the position indicated in Fig. 1 to the position indicated in Fig. 2, the 40 latter (Fig. 2) indicating the position of the craft at high speed and supported principally by air reaction on the surfaces 12, although still hydroplaning lightly on the surface of the water. As the position of the 45 machine is gradually shifted, the angle of incidence of the supporting surfaces 12 is gradually increased from two (2°) degrees to eight and a half ($8\frac{1}{2}^\circ$) degrees, the latter angularity having been calculated to exert 50 sufficient lift to pull the boat from the surface of the water while skimming thereover and without rocking the craft fore and aft. This angle of incidence ($8\frac{1}{2}^\circ$) determines 55 not only the angularity required to rise from the surface of the water but the angularity calculated as best for maximum climb. At all times, under the conditions stated, the effective line of thrust 23 and the axis 21 extend parallel and since the pontoon 11 is 60 shaped symmetrically about said axis, a minimum of head resistance, in traveling at maximum speed, is offered.

Referring now more particularly to Figs. 3 and 4, 30 designates the hull of a flying boat, 31 the supporting surfaces, 32 the em-

pennage, and 33 the support for the propelling power plant (not shown). The hydroplaning bottom of the hull 30, like the bottom of the pontoon 11, is longitudinally non-salient, thus imparting such stability to 70 the boat that it cannot be rocked about a transverse axis while hydroplaning at speed. Said bottom is stepped at intervals longitudinally as indicated at 44 to insure hydroplaning action and reduce suction and skin 75 friction. The arrangement and location of the steps may be varied as desired. The lines indicating respectively the keel line, the hull fore and aft axial line, and the chord line of the surfaces 31 I have designated 40, 41 and 42. These lines are disposed and related as pointed out hereinbefore.

By an arrangement of the various lines in the manner stated, aerial flight from the surface of the water can be had without depressing the tail of the craft before getting off of the water and without offering unnecessary resistance after aerial flight has been gained. A perfect streamlining of the flotation body is possible so long as the fore and aft axis of said body is in parallelism with the corresponding axis of the fuselage 90 10 (in an hydroaeroplane) or the effective line of thrust. The location of the step with 95 respect to the center of gravity is immaterial.

In using the term "keel line" herein I refer more particularly to a straight line joining the projecting points of the float bottom. 100

While I have herein illustrated and described certain specific measurements, it is to be understood that these measurements are given only as illustrative of an operative machine characterized as herein described. 105 These measurements may be varied considerably without departing from the spirit of the invention. Limitations other than such as are imposed by the claims are not intended to be made. Hence:

What is claimed is:

1. In an aircraft, a flotation body having a non-salient bottom, a motor, and supporting surfaces fixed permanently in such relation to said flotation body as to make an angle 115 with the keel line thereof equal at least to the angle of incidence calculated to give a lift-drift ratio sufficient to pull the craft from the surface of the water without rocking said body fore and aft.

2. In an aircraft, a flying boat having a longitudinally non-salient bottom, a motor, and supporting surfaces fixed permanently in such relation to said flotation body as to make an angle with the keel line thereof equal to the angle of incidence calculated for maximum effective lift.

3. In an aircraft, supporting surfaces, a motor, and a flotation body having a symmetrical streamline formed about an axis 130

making with the chord line of said supporting surfaces an angle equal to the flying angle of incidence for maximum speed.

4. In an aircraft, supporting surfaces, a motor, and a flotation body having a symmetrical streamline formed about an axis making with the chord line of said supporting surfaces an angle equal to the flying angle of incidence for a lift-draft ratio considerably less than maximum.

5. In a hydro-aero-machine, supporting surfaces, a propelling power plant, and a flotation body having a symmetrical streamline formed about an axis making with the chord line of said supporting surfaces an angle not greater than the angle formed by said axial line and the keel line of said body.

6. In a hydro-aero-machine, supporting surfaces, a flotation body having a longitudinally non-salient bottom and a symmetrical streamline formed about an axis making

with the chord line of said supporting surfaces an angle equal to the flying angle of incidence calculated for maximum speed, said surfaces being fixed permanently in such relation to said flotation body as to make an angle with the keel line thereof at least equal to the angle of incidence calculated to give a lift-draft ratio sufficient to pull the craft from the surface of the water without rocking said body fore and aft.

7. In a hydroaeroplane, supporting surfaces, a pontoon having a symmetrical streamline formed about an axis making with the chord line of said supporting surfaces an angle equal to the flying angle of incidence for maximum speed, and a propelling power plant having its effective thrust line in parallelism with said pontoon axis.

In testimony whereof I hereunto affix my signature.

GLENN H. CURTISS.
